(57) **CLAIM**

The ornamental design for a front portion of a disc player, as shown and described.

DESCRIPTION

FIG. 1 is a perspective view of a front portion of a disc player showing my new design;

FIG. 2 is a top plan view thereof;

FIG. 3 is a bottom plan view thereof;

FIG. 4 is a left side elevational view thereof;

FIG. 5 is a right side elevational view thereof; and,

FIG. 6 is a front elevational view thereof.

The body portions in broken lines are for illustrative purposes only and form no part of claimed design.
